Primary Examiner—Charles A. Rademaker*(74) Attorney, Agent, or Firm*—Knobbe Martens Olson & Bear LLP(57) **CLAIM**

The ornamental design for an interbody fusion device, as shown and described.

DESCRIPTION

FIG. 1 is a rear perspective view of an interbody fusion device showing my new design;

FIG. 2 is a front elevation thereof;

FIG. 3 is a rear elevation thereof;

FIG. 4 is a right-side elevation thereof; the side opposite being a mirror-image;

FIG. 5 is a top plan view thereof; and,

FIG. 6 is a bottom plan view thereof.

The broken lines which define the bounds of the claimed design form no part thereof.
